UNITED STATES PATENT OFFICE.

WALTER E. SIMMONS, OF DUQUOIN, ILLINOIS.

PICK-LOCK.

SPECIFICATION forming part of Letters Patent No. 742,507, dated October 27, 1903.

Application filed May 13, 1903. Serial No. 157,011. (No model.)

To all whom it may concern:

Be it known that I, WALTER E. SIMMONS, a citizen of the United States, residing at Du-
5 quoin, in the county of Perry, State of Illi-
nois, have invented certain new and useful
Improvements in Pick-Locks; and I do hereby
declare the following to be a full, clear, and
exact description of the invention, such as
will enable others skilled in the art to which
10 it appertains to make and use the same.

This invention relates to locks for locking
together a number of picks; and it has for its
object to provide a cheap and simple con-
struction which may be attached to different
15 numbers of picks and will hold them securely
together, other objects and advantages of the
invention being evident from the following
description.

In the drawings forming a portion of this
20 specification, and in which like numerals of
reference indicate similar parts in the several
views, Figure 1 is a perspective view of the
lock. Fig. 2 is a side elevation of a pick with
the lock in place thereon. Fig. 3 is an ele-
25 vation of the lock looking at right angles to
Fig. 2, the heads of the pick with which the
lock is engaged being in section. Fig. 4 is a
detail view showing the connection between
the arches and the band.

30 Referring now to the drawings, the present
lock, which is designed for fastening together
a number of picks, consists of a band 5, of
metal, bent into substantially oblong form
and having its parallel sides connected by
35 substantially semicircular ends, the ends of
the band being connected by means of a heli-
cal spring 6, so that the inclosure of the band
and spring may be varied in size to accom-
modate different numbers of pick-handles, it
40 being understood that the handles of the
picks to be locked are passed through the in-
closure of the band or ring, so that the heads
of the picks rest upon the band or ring.

Pivoted to the band 5 are the ends of par-
45 allel arches 7, between which the heads of
the picks are received, the heights of these
arches being such that their central portions
extend slightly above the heads of the picks,
so that the loops or eyes 8 at the central por-
50 tions of the arches may aline, so that their
common axis will lie in a plane above the
pick-heads.

To prevent removal of the handles of the

55 picks from the band 5, a locking-bar 9 is pro-
vided, said bar being passed through the eyes
of the arches after the picks have been dis-
posed with their heads between the arches,
the locking-bar lying upon the heads and the
upper ends of the handles, so that the han-
60 dles cannot be withdrawn from the heads nor
can the heads be raised from the band.

At one end of the locking-bar 9 is a head
11, which prevents the bar from being drawn
from the eyes of the arches in one direction,
and withdrawal of the bar in the opposite di-
rection is prevented by means of a padlock
12, which may be engaged with any one of a
number of eyes 13, formed in the end of the
locking-bar opposite to the head 11.

70 It will be understood that when the lock is
in place and the locking-bar is properly ad-
justed the lock cannot be removed from the
picks and the picks cannot be separated; but
when the locking-bar is withdrawn the picks
75 may be readily removed from the inclosure
of the band, and thus from the lock itself.

What is claimed is—

1. A pick-lock comprising an expandible
band, spaced arches connected to the band
and having openings in the tops thereof and
80 a locking-bar removably engaged with the
openings and lying above the band trans-
versely thereof.

2. A pick-lock comprising an expandible
band, spaced arches connected to the band
85 and extending in the same direction at one
side thereof, and a locking-bar removably en-
gaged with the arches.

3. A pick-lock comprising an expandible
band, spaced arches connected to the band
90 and extending in the same direction at one
side of the band, and a locking-bar removably
engaged with the arches, said bar having
means at one end for holding it against lon-
95 gitudinal movement in one direction and hav-
ing at its opposite end means for engagement
of a removable retaining device for holding
it against longitudinal movement in the op-
posite direction.

In testimony whereof I affix my signature 100
in presence of two witnesses.

WALTER E. SIMMONS.
